M. TOST.

IMPULSE STARTING MECHANISM AND METHOD OF OPERATING THE SAME,
APPLICATION FILED JAN. 2, 1918.

1,338,758.

Patented May 4, 1920.

UNITED STATES PATENT OFFICE.

MAX TOST, OF DETROIT, MICHIGAN, ASSIGNEE, BY MESNE ASSIGNMENTS, TO
AMERICAN BOSCH MAGNETO CORPORATION, OF NEW YORK, N. Y., A CORPO-
RATION OF NEW YORK.

IMPULSE STARTING MECHANISM AND METHOD OF OPERATING THE SAME.

1,338,758.

Specification of Letters Patent.

Patented May 4, 1920.

Application filed January 2, 1916. Serial No. 210,068.

To all whom it may concern:

Be it known that I, MAX Tost, a subject of the Emperor of Germany, residing at Detroit, in the county of Wayne, State of Michigan, have invented certain new and useful Improvements in Impulse Starting Mechanism and Methods of Operating the Same; and I do hereby declare the following to be a full, clear, and exact description 10 of the invention, such as will enable others skilled in the art to which it appertains to make and use the same.

In general an impulse starting mechanism has driving and driven members connected respectively to rotary driving and driven units and connected to each other by an impelling spring. The impulse starting mechanism also has locking mechanism for holding the driven unit against rotation 20 while the driving unit is rotating at slow speed in starting to thereby stress the impelling spring upon relative angular displacement of the units, and it also has releasing mechanism for releasing the locking mechanism at a predetermined angular position of the driving unit to thereby permit the impelling spring, then stressed, to impel the driven unit through an appropriate angle and at a comparatively high speed, 30 even though the driving unit may at the time of release be rotating at slow speed or at rest.

It is sometimes necessary to repeat the impelling movement one or more times. For 35 instance, in the case of a magneto driven by the internal combustion engine with which it is associated for ignition purposes, it sometimes happens that the engine is not started into operation under its own power 40 by the first spark even though the cylinders are primed and the spark generated in the impelling movement would ordinarily be satisfactory for ignition. A second spark is then required, or a third or even a fourth 45 may be required under extremely adverse conditions, such as cold cylinder walls, low compression, improper mixture, high static friction, etc. To turn the engine over to another firing point involves the rotation 50 of 720° for the same cylinder, or 180° for the next cylinder in the firing order of a four-cylinder engine, wherein, as usual, the engine operates on the 4-cycle plan.

This method of repeating the impelling

movement of the impulse starting mechanism by turning the driving unit over to restress the impelling spring, was the method heretofore practised although it is unsatisfactory in many organizations, especially in an engine organization where an engine starter is not employed, as, for example, in the case of tractor engines, which usually have to be turned over with a crew bar, and which are subjected to rough handling in use and improper protection when not in use.

In accordance with my invention, the above noted disadvantage of the prior method of repeating the impelling movement of an impulse starting mechanism by 70 rotating the driving unit to restress the impelling spring is entirely obviated by disconnecting the driving and driven units from each other so that the impelling spring may be restressed as often as desired without turning the driving unit for that purpose. The driving and driven units may be disconnected by means of a releasable coupling arranged in the mechanical connection between them, and preferably the coupling 75 is arranged on the driving side of the impulse starting mechanism, so that that mechanism and the driven unit are disconnected from the driving unit when the impelling spring is to be restressed. Thus, in 80 an engine organization of the kind hereinbefore pointed out, a cylinder may be re-fired repeatedly until the engine starts into operation under its own power, while constantly maintaining the engine in its firing 85 position, the magneto being returned each time to its angular position for maximum generation during the subsequent impelling movement.

Although in returning the driven unit to 90 a predetermined angular relation with respect to the driving unit, preliminarily to repeating the impelling movement, it is possible in some installations to turn the driven unit in the normal direction of rotation produced by the driving unit, I prefer to turn the driven unit against the normal direction of rotation. Likewise, I prefer to restress the impelling spring subsequent to the returning movement of the driven unit, al- 100 though it is possible to do both in the same period of operation. Thus, when a coupling is installed between the impulse starting

- mechanism and the engine, to disconnect that mechanism and the magneto from the engine in order to refire a cylinder, I prefer to first turn the magneto against the normal direction of rotation to its angular position for maximum generation, and then to restress the impelling spring in returning the driven member of the coupling for reconnection to the other coupling member.
- 10 In this restressing period, the magneto is held in its returned position by the locking mechanism of the impulse starting mechanism, and when the spring is restressed and the coupling members reconnected, the magneto and engine are maintained in their predetermined angular relation, pending the operation of the releasing mechanism, as a result of the resistance of the engine to angular movement.
- 15 This invention not only comprehends the foregoing methods of operating the impulse starting mechanism in repeating the impelling movements thereof, but it also comprehends suitable apparatus for carrying out 20 those methods, in all suitable organizations including driving and driven units and impulse starting mechanism therebetween.
- 25 In the accompanying drawings illustrating suitable apparatus of this kind in application, as an example, to an engine organization,
- 30 Figure 1 is an elevation showing in section the magneto, the impulse starting mechanism therefor, and the coupling installed, as an example, on the driving side of the 35 impulse mechanism; Fig. 2 is a side elevation of the coupling on an enlarged scale; Fig. 3 is a top view of the coupling; and Figs. 4, 5 and 6 are diagrammatic views indicating the relative positions of parts of the impulse starting mechanism and the coupling, during the restressing period 40 while the coupling members are disconnected.
- 45 In the drawings, the engine 1 is of the 4-cylinder 4-cycle type driving a bipolar magneto 2 through like gears 3, the releasable coupling 4, and the impulse starting mechanism 5.
- 50 The magneto and the impulse starting mechanism therefor are identical with the disclosure in the application of W. E. Schwarzmann, Serial No. 192,461, filed September 21, 1917, but, like the engine 55 and the coupling, may be of any type suitable for employment in accordance with this invention.
- 60 The magneto has an armature 6 rotatable on an axis extending along the length of the arms of the magnet 7. The impulse starting mechanism is inclosed by a housing 8 at the outer ends of the magnet. The driving member 9 and the driven member 10 of the coupling are fixedly mounted on 65 the coaxial shafts 11 and 12, and the spring

plate latches 13 are pivoted to the driving member so that they can be moved from engaged positions connecting the two coupling members, as shown in full lines in Fig. 1, to the disengaged positions shown in broken lines in Fig. 1 for disconnecting from the engine the magneto, the impulse starting mechanism, and the driven coupling member. The flat springs 14 tend to hold the latches in either engaged or disengaged positions.

70 The driving member 26 of the impulse starting mechanism is fixed on the shaft 12 and carries the impelling and buffer springs 15 and 16, and the interposed abutments 17, together with the releasing cams 18. The driven member 27 of the impulse starting mechanism is fixed on the magneto shaft 19 and carries the safety cams 20. The pressure applying arm 21 is loosely journaled on the driving member of the impulse starting mechanism and extends through slots in the driven member to turn therewith. The releasing cams, the safety cams, and the outer ends of the pressure applying arm coact with the locking pawl 22, which may be turned by the handle 23 between its locking positions shown in Figs. 5 and 6 and its raised inoperative position shown in Fig. 4.

95 The impulse starting mechanism operates as follows for rotation in clockwise direction as viewed from the right in Fig. 1: The driving and driven members are fixed on their shafts in such position that one of the safety cams 20 first comes under the pawl, followed by one end of the pressure applying arm 21, and then by one of the releasing cams 18. At slow speed in starting, the pawl 22, when in engaging position, rides smoothly on the safety cam and remains in position to engage the pressure applying arm. At this position the arm, and therefore the driven member fixed on the armature shaft, are locked against rotation with the armature poles substantially bridging the spaces between the field poles, that is a little prior to its angular position for maximum generation. Likewise the 100 mechanical interrupter 24 is near its position to start its interrupting movement. Further movement of the driving member of the impulse starting mechanism causes the abutments 17 to compress the impelling spring between them and the pressure applying arm, until the pawl 22 is lifted by one of the releasing cams 18, or by the handle 23, to release the spring for its impelling movement of the magneto armature, the engine being so timed that one of its cylinders is at its firing point when the releasing cam releases the pawl. The impelling movement causes a sufficiently high speed of the armature irrespective of the speed 105 of the driving member at the time, and 110

through an appropriate angle, to generate an ignition voltage ordinarily capable of producing a satisfactory spark at the spark plug in the cylinder to which it is connected 5 through the magneto distributor and connecting wires. Usually the combustible mixture in that cylinder is ignited and the engine started into operation under its own power. If, for any reason, however, the engine does not start into action, one or more sparks are required.

In accordance with the invention, the same cylinder may be refired, as often as desired, while maintaining the engine in fixed angular position. To do this, the timing is such that the pistons reach the beginning of their power strokes just prior to the time a releasing cam starts to lift the pawl 22, as indicated in Fig. 6, and the magneto is in its angular position for maximum generation during the subsequent impelling movement by the spring, then stressed. After each unsuccessful impelling movement, the angular positions of the engine, the coupling, and the driving member of the impulse starting mechanism, are unchanged, but the pressure applying arm and the magneto armature are in advanced positions to which they were impelled by 25 the spring, as indicated in Fig. 4. The coupling members are then disconnected by releasing the latches 13, and the driven member of the coupling, together with the magneto armature and both members 26, 27 of 30 the impulse starting mechanism, are turned back in an anti-clockwise direction until the pressure applying arm is in position to be locked against rotation by the pawl 22, the magneto armature, thus being returned to 35 its position for maximum generation. The parts then have the angular positions indicated in Fig. 5, and the armature, the pressure applying arm, and the safety cams are locked in their positions by the pawl. Now 40 upon turning the driven coupling member in the opposite direction, that is, in the normal clockwise direction of rotation, the driving member 26 of the impulse starting mechanism is turned and the impelling 45 spring restressed between the abutments 17 and the pressure applying arm 21, until the releasing cam 18 is again at or near the position at which it starts to lift the pawl, as indicated in Fig. 6. The driving member 50 of the coupling will then be in position for the latches 13, to reconnect the magneto to the engine. When this has been done, the impelling spring is held in fully restressed condition as a result of the resistance of the 55 engine to turning. To repeat the impelling movement, the impelling spring is then released by raising the pawl 22 by means of the handle 23, whereupon the magneto is impelled to generate another spark in the 60 same cylinder.

This operation may be repeated as often as necessary, but when the engine does start into operation under its own power, the pawl may be raised into inoperative position in engagement with the latch 25, by 70 turning the handle 23, or the pawl will be automatically thrown to that position by one of the safety cams 20, if the pawl should be in position to engage the pressure applying arm when the engine reaches an unsafe 75 speed for that occurrence. After starting into action, the engine drives the magneto without any substantial lag through the reconnected coupling and the impelling spring of the impulse starting mechanism. 80 Having thus described my invention, what I claim is:

1. The method of repeating the impelling movement of an impulse starting mechanism arranged between rotary driving and driven units, which consists in disconnecting the units from each other, restressing the impelling spring of the impulse starting mechanism while maintaining the driving unit at rest, reconnecting the units, and finally releasing the restressed impelling spring.

2. The method of repeating the impelling movement of an impulse starting mechanism arranged between rotary driving and driven units, which consists in disconnecting the units from each other, turning the driven unit and restressing the impelling spring of the impulse starting mechanism while maintaining the driving unit at rest, reconnecting the units, and finally releasing the restressed impelling spring.

3. The method of repeating the impelling movement of an impulse starting mechanism arranged between rotary driving and driven units, which consists in disconnecting the units from each other, turning the driven unit to bring it to a predetermined angular relation with respect to the driving unit, restressing the impelling spring of the impulse starting mechanism, reconnecting the units, and finally releasing the restressed impelling spring.

4. The method of repeating the impelling movement of an impulse starting mechanism arranged between rotary driving and driven units, which consists in disconnecting the units from each other, turning the driven unit against the normal direction of rotation to bring it to a predetermined angular relation with respect to the driving unit, restressing the impelling spring of the impulse starting mechanism, reconnecting the units, and finally releasing the restressed impelling spring.

5. The method of repeating the impelling movement of an impulse starting mechanism arranged between rotary driving and driven units, which consists in disconnecting the units from each other, turning the driven unit to bring it to a predetermined angular

- relation with respect to the driving unit while maintaining the driving unit at rest, restressing the impelling spring of the impulse starting mechanism, reconnecting the units in the predetermined angular relation, and finally releasing the restressed impelling spring.
6. The method of repeating the impelling movement of an impulse starting mechanism arranged between rotary driving and driven units, which consists in disconnecting the impulse starting mechanism from the driving unit, turning the driven unit and restressing the impelling spring of the impulse starting mechanism while maintaining the driving unit at rest, reconnecting the impulse starting mechanism to the driving unit, and finally releasing the restressed impelling spring.
7. The method of repeating the impelling movement of an impulse starting mechanism arranged between rotary driving and driven units, which consists in disconnecting the impulse starting mechanism from the driving unit, turning the driven unit to bring it to a predetermined angular relation with respect to the driving unit, restressing the impelling spring of the impulse starting mechanism while maintaining the driving unit at rest, reconnecting the impulse starting mechanism to the driving unit, and finally releasing the restressed impelling spring.
8. The method of repeating the impelling movement of an impulse starting mechanism having driving and driven members connected respectively to rotary driving and driven units, which consists in disconnecting the impulse starting mechanism from the driving unit, turning the driving member of the impulse starting mechanism against the normal direction of rotation to bring the driven unit to a predetermined angular relation with respect to the driving unit, then turning the driving member of the impulse starting mechanism in the opposite direction to restress the impelling spring while maintaining the units in that angular relation, reconnecting the impulse starting mechanism to the driving unit, and finally releasing the restressed impelling spring.
9. The method of refiring a cylinder of an internal combustion engine by means of a rotary magneto connected thereto through an impulse starting mechanism, which consists in disconnecting the magneto from the engine, returning the magneto to its position for maximum generation during the subsequent impelling movement while maintaining the engine in its firing position, restressing the impelling spring of the impulse starting mechanism, reconnecting the magneto to the engine, and finally releasing the restressed impelling spring.
10. The method of refiring a cylinder of an internal combustion engine by means of a rotary magneto connected thereto through an impulse starting mechanism, which consists in disconnecting the magneto from the engine, returning the magneto to its position for maximum generation during the subsequent impelling movement while maintaining the engine in its firing position, restressing the impelling spring of the impulse starting mechanism, reconnecting the magneto to the engine, and finally releasing the restressed impelling spring.
11. The method of refiring a cylinder of an internal combustion engine by means of a rotary magneto connected thereto through an impulse starting mechanism, which consists in disconnecting the impulse starting mechanism from the engine, returning the magneto to its position for maximum generation during the subsequent impelling movement while maintaining the engine in its firing position, restressing the impelling spring of the impulse starting mechanism, reconnecting the impulse starting mechanism to the engine, and finally releasing the restressed impelling spring.
12. The method of refiring a cylinder of an internal combustion engine by means of a rotary magneto connected thereto through an impulse starting mechanism, which consists in disconnecting the impulse starting mechanism from the engine, turning the magneto to its position for maximum generation during the subsequent impelling movement while maintaining the engine in its firing position, restressing the impelling spring of the impulse starting mechanism, reconnecting the impulse starting mechanism to the engine, and finally releasing the restressed impelling spring.
13. The combination of rotary driving and driven units, impulse starting mechanism arranged between the driving and driven units, and a releasable coupling arranged between the impulse starting mechanism and one of said units; substantially as and for the purpose described.
14. The combination of rotary driving and driven units, impulse starting mechanism arranged between the driving and driven units, and a releasable coupling arranged between the driving unit and the impulse starting mechanism; substantially as and for the purpose described.
15. The combination of an internal combustion engine, a rotary magneto therefor, impulse starting mechanism arranged between the engine and magneto, and a releasable coupling arranged between the engine and the impulse starting mechanism; substantially as and for the purpose described.

In testimony whereof I affix my signature.
MAX TOST.
